UNITED STATES PATENT OFFICE.

CHARLES STRAND AND JOHN GILBURG, OF FOWLER, INDIANA.

CARTRIDGE-LOADING MACHINE.

SPECIFICATION forming part of Letters Patent No. 321,257, dated June 30, 1885.

Application filed April 27, 1885. (No model.)

To all whom it may concern:

Be it known that we, CHARLES STRAND and JOHN GILBURG, both residents of Fowler, in the county of Benton and State of Indiana, have 5 invented certain new and useful Improvements in Machines for Loading Shells for Guns; and we do hereby declare that the following is a full, clear, and exact description of the invention, which will enable others skilled in the art to 10 which it appertains to make and use the same, reference being had to the accompanying drawings, which form a part of this specification, and in which—

Figure 1 is a front view of our improved 15 cartridge-loading machine. Figs. 2 and 3 are side views of the same. Fig. 4 is a vertical sectional view on line $x-x$, Fig. 1. Fig. 5 is a horizontal sectional view on line $y-y$, Fig. 1. Fig. 6 is a similar view on line $z-z$, Fig. 1, 20 showing the cartridge-holding casing in its horizontal position for crimping the shell. Figs. 7 and 8 are perspective detail views of the slide for covering the lower end of the cartridge-holding casing, and Fig. 9 is a vertical sectional detail view of the powder and 25 shot tubes.

Similar letters of reference indicate corresponding parts in all the figures.

Our invention has relation to machines for 30 filling the shells of cartridges, especially adapted for filling shells used in shotguns; and it consists in the improved construction and combination of parts of the same, as hereinafter more fully described and claimed.

In the accompanying drawings, the letter A 35 indicates a vertical upright, which is formed at its lower portion with two rearwardly-projecting lugs, B and C, the lower one, C, of which has a vertical screw-threaded perforation, D, in which turns a set-screw, E, by means of which the upright may be clamped upon a table or similar article. At the upper portion of the upright is secured a rearwardly-projecting platform, F, having two perforations, G and H, which are surrounded by two upwardly-projecting sleeves or tubes, I and J, upon which two tubes, K and L, fit and slide, having set-screws M, for adjusting them upon the aforesaid tubes. The downwardly-projecting tubes N N of two hoppers or funnels, O 40 and P, fit into the upper ends of the tubes K

and L, and the said tubes K and L are formed with diametrically-opposite transverse slots Q, in which two slides, R R, slide, the said slides having perforations S at one end, which 55 correspond to the interior diameter of the tubes. Similar slides, T T, slide under the platform, under the apertures in the same, and have apertures U, corresponding to the apertures in the platform, but in the ends of the 60 slides opposite to the apertures in the upper slides, so that when the slides are moved simultaneously the lower slides will bring their apertures to register with the apertures in the platform, while the apertures in the upper 65 slides will appear outside of the tubes, and the solid parts of the slides will close the tubes. The upper slides have rods V V projecting from their rear ends and fitting in perforations W in the rear ends of the lower slides, and the 70 perforated laterally-bent rear ends of two rods, X and Y, have these vertical rods passing through them, the forward ends of the horizontal rods X and Y sliding in horizontal bearings Z in a frame, A', at the side of the platform, 75 and having knobs B' C' at their outer ends, and having springs D' for forcing them forward. It will thus be seen that by forcing either of these rods back against its spring the corresponding slides will be forced back so as to 80 close the upper telescoping tube and open the aperture in the platform, allowing the powder or shot which may be in the corresponding hopper to fall out of the lower end of the telescoping tube, the upper end of which is cut 85 off from the hopper. It will also be seen that the telescoping tubes may be adjusted upon the tubes upon the platform, so as to adjust them to the quantity of the charge desired by means of the set-screws in the sliding tubes, 90 and by means of the vertical rods sliding in the perforations in the rear ends of the slides and moving freely in the perforations in the rear ends of the push-rods. A funnel, E', is secured with its flaring mouth to the under 95 side of the platform, and has a tube, F', passing into a cylinder, G', secured vertically upon the forward side of the upright, and provided with a piston or rammer, H', sliding vertically in the cylinder. This rammer has a 100 vertical rod, I', to the upper end of which is articulated a connecting-rod, J', the upper end

of which is articulated to a lever, K', the inner end of which is pivoted to the end of a rearwardly-projecting bracket or arm, L', upon the upper end of the upright, and provided 5 at its forward end with a handle, M'. The shell - holding casing N' is pivoted with a trunnion or bearing, O', projecting laterally from its middle, upon the lower end of the upright, swinging in a vertical plane, and is provided 10 with a slide, P', at its lower end, which will be described hereinafter. The upper end of this casing bears, when in its vertical position, against the lower end of the charging cylinder G', and a laterally-projecting horizontal platform, Q', is secured at the lower end of the said cylinder, which is provided 15 with a horizontal slot, R', the lower edge of which is flush with the platform. A wad-carrying arm, S', is secured adjustably with its rear end upon a rod, T', sliding in a horizontal bearing in the upright, and has its forward end sliding upon the upper face of the platform, the rear end having a horizontal perforation, U', which fits upon the horizontally-sliding rod and a set-screw, V'. The other 20 end of this horizontally-sliding rod is formed with two forwardly-projecting lips, forming a notch, W', between them, and a rod, X', is connected at its upper end to the upper end of the rammer-rod, and slides in a vertical bearing, Y', upon the side of the charging-cylinder, and the lower end of this rod is provided 25 with a plate, Z', having a rearwardly-bent inclined flange, A', at its outer edge, at its lower end, which flange engages the notch between the lips, and, by being inclined, diverging from the upper end of the charging-cylinder, will force the horizontally-sliding rod to the side, drawing the wad-carrying arm 30 toward the slot in the end of the charging-cylinder when the rammer is forced down, while it will force the rod and its wad-carrying arm from the slot when it is raised with the rammer. The lower end of the upright is provided with 35 a transverse horizontal bearing, in which slides a bar, B'', one end of which is provided with a forwardly-projecting arm, C'', the forward end of which forms a horizontal bearing, D'', in which turns the crimper-shaft E'', the outer end of which is provided with a crank, F'', while its inner end is shouldered, as shown at G', the shoulder bearing against 40 the end of the shell and turning it in, when in operation, while the reduced part will fit into the open end of the shell. The other end of the horizontally-sliding bar is provided upon its upper side with a bail, H'', into which projects the rear end of a lever, I'', pivoted to swing horizontally upon 45 an arm, J'', projecting forwardly from the bearing-frame K'' upon the lower end of the upright, so that the crimper may be drawn into the open end of the shell-holding casing, when the latter is turned into its horizontal 50 position, turning the edges of the shell inward, whereupon, by revolving the crimper-shaft 55 60 65

and at the same time forcing it into the shell and casing, the edge will be turned so as to retain the wad. The slide P', which closes the lower end of the shell-holding cylinder or 70 casing, is pivoted to swing transversely across the end of said casing, and has an outwardly-projecting handle, L'', at its free end, upon the upper side of which handle a catch-lever, M'', is pivoted, the inner end of which lever 75 has a tongue, N'', which bears against the upper side of a flange, O'', around the lower end of the casing, and a beveled end, P'', which engages a notch, Q'', in the said flange, when the slide is covering the end of the casing, and 80 a spring, R'', bears against the outer end of this catch-lever and forces it to engage the notch. The pivotal pin S'', upon which this catch-lever turns in a vertical perforation in the handle of the slide, is provided at its 85 lower end with an inwardly-projecting arm, T'', the free end of which may be engaged by a thumb-lever, U'', pivoted at its inner end upon the under side of the slide, so that by forcing the said thumb-lever toward the handle of the slide it will tilt the arm of the catch-lever and disengage the same from its notch and allow the slide to be swung to the side, opening the end of the shell-holding casing, so as to allow a shell to be inserted or 90 a loaded shell to be withdrawn. It will thus be seen that the shell may be inserted into the shell-holding casing, which is placed in its vertical position, the slide of the powder-hopper pushed back, a wad placed upon the 100 platform or slide for its reception, when by depressing the lever, and through it the rammer, the inclined flange will draw the wad-carrying rod and arm to force the wad through the slot in the end of the charging-cylinder, 105 whereupon the descending rammer will ram the load in the shell. The same performance is repeated with the shot-charge, when the shell-holding cylinder is turned into its horizontal position and the crimper drawn into 110 the open end of the said cylinder and into the shell, when by turning the crank of the crimper-shaft the edge of the shell will be doubled inward and crimped to retain the outer wad. 115

Having thus described our invention, we claim and desire to secure by Letters Patent of the United States—

1. In a cartridge-loading machine, the combination of a rigid discharge-tube, a cut-off slide reciprocating across the lower end of the said tube, a tube sliding upon the aforesaid tube and having a set-screw for adjusting it upon the same, a hopper opening into the said sliding tube, a cut-off slide sliding in a transverse slot in the adjustable tube, and having a rod projecting from one end sliding in a perforation in the corresponding end of the lower cut-off slide, and a rod having its perforated end fitting upon the rod connecting the slides 120 for reciprocating the slides simultaneously, as and for the purpose shown and set forth. 125 130

2. In a cartridge-loading machine, the combination of the platform having the perforations G and H, tubes I and J, projecting from the said perforations, tubes K and L, having the set-screws and sliding adjustably upon the aforesaid tubes, the hoppers O and P, the slides R T and R T, sliding in the transverse slots Q in the sliding tubes and at the lower ends of the tubes I and J, rods V, projecting downward from the rear ends of the upper slides, and fitting in perforations in the rear ends of the lower slides, and the horizontal operating-rod X and Y, having knobs at their forward ends and springs for forcing them forward, and having their bent rear ends provided with perforations fitting upon rods V, as and for the purpose shown and set forth. 45
- 5 10 15 20 25 30 35 40
3. In a cartridge-loading machine, the combination of a charging-cylinder, a rammer reciprocating in the same, a platform secured at the lower end of the charging-cylinder at the lower edge of a transverse slot in the same, a rod sliding in a bearing transverse to the cylinder, and provided at one end with an arm sliding upon the platform and at the other end with projecting lips, forming a notch between them, and a plate secured at the lower end of a rod sliding parallel with the rammer, and having an inclined flange at its outer end for engaging the said notch, as and for the purpose shown and set forth. 50
4. In a cartridge-loading machine, the combination of the charging-cylinder having a transverse slot at its lower end and a platform projecting from the lower edge of the said slot, a tube passing from the powder and shot hoppers into the lower end of this cylinder, a cylinder for supporting the shell below the lower end of the cylinder, a rammer reciprocating in the charging-cylinder, a rod sliding transversely to the cylinder, and having at one end a wad-carrying arm sliding upon the platform at the end of the cylinder, and having lips at 55 60 65 70 75
- its other end formed with a notch between them, and a rod secured to the rammer and sliding parallel with the same, and provided at its lower end with a plate having its outer edge provided with a flange inclined with its upper end away from the upper end of the cylinder engaging the notch, as and for the purpose shown and set forth. 50
5. In a cartridge-loading machine, the combination of the shell-holding casing, the sliding bar having the crimping-shaft journaled in its forwardly-projecting arm and provided at the other end with the bail, the crimping-shaft having the shouldered inner end and having the crank at its outer end, and the lever having its inner end engaging the bail upon the sliding bar, as and for the purpose shown and set forth. 55
6. The combination of the cylinder for holding the shell, having the flange at its lower end formed with a notch, the slide pivoted at its inner end to swing under the end of the cylinder and having the outwardly-projecting arm at its outer end, the catch-lever having the lip at its inner beveled end for resting upon the upper side of the flange of the cylinder and having the spring bearing against its outer end, the pivotal pin of the catch-lever turning in a perforation in the arm of the slide and having an inwardly-projecting arm at its lower end, and the thumb-lever pivoted at the inner end of the swinging slide and bearing against the arm of the pivotal pin, as and for the purpose shown and set forth. 65 70 75

In testimony that we claim the foregoing as our own we have hereunto affixed our signatures in presence of two witnesses.
